UNITED STATES PATENT OFFICE.

TRUMAN C. SHERWOOD, OF DANVILLE, ILLINOIS, ASSIGNOR OF FORTY-NINE ONE-HUNDREDTHS TO HUBERT R. VAN NORDSTRAND, OF DANVILLE, ILLINOIS.

FURNACE.

Application filed October 1, 1923. Serial No. 665,914.

To all whom it may concern:

Be it known that I, TRUMAN C. SHERWOOD, a citizen of the United States, residing at Danville, in the county of Vermilion and State of Illinois, have invented certain new and useful Improvements in Furnaces, of which the following is a specification.

This invention relates to furnaces, and more particularly to pipeless furnaces.

10 An object of the invention is the provision of a furnace of this character having an improved air feed whereby substantially complete combustion is obtained, with resulting economy in fuel.

15 A further object is to provide a furnace in which fresh air drawn from the outside is heated and delivered to the building and air withdrawn from the building is superheated and employed in the fire box to support combustion.

20 In the accompanying drawings, I have shown one embodiment of the invention. In this showing:

Figure 1 is a front elevation,

25 Figure 2 is a central vertical sectional view,

Figure 3 is a horizontal sectional view on line 3—3 of Figure 2,

Figure 4 is a similar view on line 4—4 of 30 Figure 2, and,

Figure 5 is a similar view on line 5—5 of Figure 2.

Referring to the drawings, the reference numeral 1 designates an outer casing which is preferably cylindrical and which extends from the floor 2 of the cellar to the first floor 3 of the building to be heated. The casing is provided with a fresh air chamber 4 at the bottom, which is connected to the outside of the building by means of a pipe 5. The chamber is provided with an outlet 6 communicating with an air heating space or passage 7. As shown, the air heating space or passage is formed by an inner cylindrical shell 8 spaced from the outer shell and a furnace cylinder 9. Within the furnace cylinder, there is provided the usual grate 10, the cylinder above the grate forming a fire box 11 which is provided with the usual outlet stack 12. The top of the shell or casing 1 is provided with a grating or register 13 arranged in the floor 3, and air from the room is withdrawn through space 14 between the outer shell 1 and the inner shell 8. The bottom of the inner shell is flared, as at 15,

forming a restricted passage through which this withdrawn air passes. The lower air chamber is provided with a top plate 16, extending across the furnace beneath the grate and a wall 17 extends upwardly from this plate, substantially parallel to the flared portion of the bottom of the shell 8. This forms an air passage 18 for the withdrawn air, part of which passes through a passage 19 under the grate. The remaining portion of the withdrawn air passes through a passage 20 between the furnace cylinder and a shell or cylinder 21 surrounding the grate. This air is superheated and passes through openings 22 into the fire box combining with the gases formed from the combustion of the fuel and producing substantially perfect combustion. The fresh air from the passage 7 is heated by conduction and radiation and passes outwardly through the central portion 75 of the register 13 into the room to be heated.

The operation of the device will be apparent from the foregoing description. The continual supply of fresh air from the exterior affords pure air for heating at all 80 times and thus serves as a ventilating device as well as a heating apparatus. This air is heated during its travel through the passage or chamber 7 and thoroughly heats the room in which it is admitted. The withdrawn air 85 passing through the passage 14 supplies the oxygen for the initial combustion of the fuel by means of the air passing through the passage 19 under the grate, and then supplies additional preheated air to the fire box 11 90 through the openings 22 to completely consume the gases, such as carbon monoxide in the products of combustion from the grate. By extending the passages 19 and 20 entirely around the furnace, an even distribution of 95 air is obtained and thus even burning of the fuel in the fire box is obtained.

It is to be understood that the form of my invention herewith shown and described is to be taken as a preferred example of the same, and that various changes in the shape, size, and arrangement of parts may be resorted to without departing from the spirit of the invention or the scope of the subjoined claims.

I claim:

1. In a pipeless furnace, an outer casing, an air chamber arranged beneath said casing, an inner casing, a furnace cylinder arranged within said inner casing and spaced there-

from to form a heating chamber, means for feeding air from said air chamber to said heating chamber, and means for returning air from the room heated to the fire box of 5 the furnace.

2. In a pipeless furnace, an inner casing and an outer casing forming a return passage, a furnace cylinder arranged within said inner casing and spaced therefrom to form 10 a heating chamber, a passage connecting said return passage to the ash pit of the furnace, means for delivering air from said last passage to the fire box and preheating it, and means for delivering fresh air to said 15 heating chamber.

3. In a pipeless furnace, an inner casing and an outer casing forming a return passage, a furnace cylinder arranged within 20 said inner casing and spaced therefrom to form a heating chamber, a passage connecting said return passage to the ash pit of the furnace, a passage within said furnace chamber connected to said last mentioned passage

extending around the grate of the furnace to the fire box to preheat air and deliver it to 25 the fire box, and means for delivering fresh air to said heating chamber.

4. In a pipeless furnace, an inner casing and an outer casing, forming a return passage, a furnace cylinder arranged within 30 said inner casing and spaced therefrom to form a heating chamber, a passage connecting said return passage to the ash pit of the furnace, means for delivering air from said last passage to the fire box and preheating it, 35 an air chamber arranged beneath said furnace and connected to said heating chamber, and an air pipe connecting said air chamber to the exterior of the building to be heated.

In testimony whereof, I affix my signature in presence of two witnesses.

TRUMAN C. SHERWOOD.
